OIL BURNING HEATER

Benjamin H. Turner, Corryton, Tenn.

Application August 22, 1952, Serial No. 305,741

1 Claim. (Cl. 126—110)

This invention relates to space heaters, and more particularly to an improved space heater of the liquid fuel type.

A main object of the invention is to provide a novel and improved space heater which is simple in construction, which is safe to use, and which is efficient in operation.

A further object of the invention is to provide an improved oil burning space heater which is inexpensive to manufacture, which is sturdy in construction, and which is economical in fuel consumption.

Further objects and advantages of the invention will become apparent from the following description and claim, and from the accompanying drawings, wherein:

Figure 1 is a side elevational view of an improved space heater constructed in accordance with the present invention.

Figure 2 is a horizontal cross sectional view taken on the line 2—2 of Figure 1.

Figure 3 is a vertical cross sectional view taken on the line 3—3 of Figure 1.

Figure 4 is a horizontal cross sectional view taken on the line 4—4 of Figure 1 in the direction of the arrows indicated in Figure 1.

Referring to the drawings, the improved space heater is designated generally at 11 and comprises a vertically disposed tubular casing 12 having the generally Z-shaped supporting legs 13 secured to the bottom rim thereof, as illustrated in Figures 1 and 2, to support the casing 12 in a stable position. Designated at 14 is a relatively obtuse conical baffle plate which is secured at its periphery to the intermediate portions of the respective supporting legs 13, whereby said baffle plate is secured in horizontal position with its apex directed upwardly as is clearly shown in Figure 3. The casing 12 has the annular bottom wall 15 and the annular top wall 16. Integrally formed with the top wall 16 and depending axially through the tubular casing 12 is the downwardly tapering vertical air conduit 17 which is secured at its bottom rim to the upturned annular inner rim 18 of the bottom wall 15. From Figure 3 it will be seen that an annular air discharge passage is defined between the baffle plate 14 and the bottom wall 15 of the tubular casing 12.

Secured to the upper portion of the tubular casing 12 is a supporting bracket 19 on which is mounted an electrically driven air blower 20 having an outlet conduit 21 on which is rotatably secured the air discharge tube 22, said discharge tube being provided with an elbow-shaped discharge nozzle 23. As shown in Figure 3, the discharge tube 22 may be positioned so that the discharge nozzle 23 points downwardly through the downwardly tapering conduit 17 to provide a maximum discharge of air through said conduit, or alternatively may be rotated to any selected angular position providing a reduced rate of air flow through the conduit 17. The air blower 20 is provided with the screened inlet port, shown at 24, whereby air may be drawn into the blower from the atmosphere.

Mounted on the bottom wall 15 of the tubular casing 12 concentrically with the conduit 17 is the apertured

2

annular shell 25 which is provided with the inturned, serrated top rim 26. Secured on the annular bottom wall 15 of the casing 12 in the lower portion of the shell 25 is the annular fuel trough 27 arranged concentrically with the shell 25 and formed with a bottom channel 28 adapted to engage the bottom wall 15 and to be secured thereto in any suitable manner, as by welding or the like.

It will be readily understood that the annular trough 27 is adapted to contain a quantity of liquid fuel, such as fuel oil, for combustion in the annular space defined by the shell 25. The lower portion of the tubular casing 12 is formed with the air intake louvers 29 through which air may be admitted into the casing for entry into the shell 25 through the apertures thereof to combine with the vaporized fuel and to promote the combustion of the fuel.

Connected to the top portion of the tubular casing 12 is the flue 30 through which the draft gases from the fuel burner are discharged, said flue being provided with conventional draft valve means, shown at 31 for regulating the draft through the flue. The upper space in the tubular casing 12 to which the flue 30 is connected is designated at 32. The upper space 32 is defined by a horizontal annular partition wall 33 which is secured in the casing 12 around the vertical air conduit 17, as shown in Figure 3, the partition plate 33 being formed with a relatively large notch 34 to allow the products of combustion to pass upwardly into the space 32 and thus escape from the burner through the flue 30.

In operation of the device, the blower 20 provides circulation of the air downwardly through the tapering conduit 17, the air discharging from the heater through the outwardly flaring annular space defined between the baffle plate 14 and bottom wall 15. In its passage downwardly through the heater, the air is heated by the gaseous products of combustion rising from the fuel burner along the external surface of the air conduit 17. The gaseous products of combustion are distributed and diffused along the external surface of the conduit 17 by the serrations 40 of rim 26.

Fuel is admitted to the burner trough 27 from a fuel supply conduit 35 through a manually controlled valve 36 which may be adjusted to regulate the supply of fuel to the burner trough.

When it is desired to adapt the burner for the use of gas as a fuel instead of a liquid fuel, the annular trough 27 may be replaced by an annular, perforated hollow gas burner which may be connected to a suitable source of gas fuel, whereby the gas fuel may be admitted into the burner shelf 25 for combustion in the same manner as described in connection with the use of liquid fuel.

While a specific embodiment of an improved space heater has been disclosed in the foregoing description, it will be understood that various modifications within the spirit of the invention may occur to those skilled in the art. Therefore it is intended that no limitations be placed on the invention except as defined by the scope of the appended claim.

What is claimed is:

60. In a space heater, an air heater structure of the down-flow type comprising an outer casing and an inner conduit both of tubular formation and both arranged vertically in spaced, concentric relation to define an annular combustion space therebetween, said inner conduit having its opposite ends formed open, the lower end of the conduit lying in a horizontal plane; top and bottom end walls extending between and connecting the casing and conduit at the ends thereof to close said combustion space for burning fuel to heat air passing through said conduit; blower means operatively associated with said conduit adapted for drawing air into the upper end of the conduit and for forcing the air through the conduit and

3

out the lower end thereof, said bottom end wall being wholly flat and lying in a horizontal plane common to that of the lower end of the conduit; upstanding legs spaced circumferentially of, and attached at their upper ends to, the outer periphery of the bottom wall to support the bottom wall in an elevated position; and a circular, obtusely conical baffle plate concentric with the bottom wall and having its periphery secured to the legs below and in spaced relation to said outer periphery of the bottom wall, thus to define between said baffle plate and bottom wall an annular passage increasing progressively in depth in a radial direction, into which passage air deflected by the baffle plate will be directed, to pass radially and outwardly of said passage after movement

of the air out of the conduit, said baffle plate having its apex extending substantially into the plane of the bottom wall to form the passage to a minimum depth at the inlet thereof.
